US0D1076745S

(12) **United States Design Patent** (10) **Patent No.:** **US D1,076,745 S**
(45) **Date of Patent:** **** May 27, 2025**

(54) **SET OF VEHICLE DOORS**

- (71) Applicant: **Oshkosh Corporation**, Oshkosh, WI (US)
(72) Inventors: **Jesse Gander**, Larsen, WI (US); **Christopher Yakes**, Oshkosh, WI (US)
(73) Assignee: **Oshkosh Corporation**, Oshkosh, WI (US)
(**) Term: **15 Years**
(21) Appl. No.: **29/888,802**
(22) Filed: **Apr. 5, 2023**

Related U.S. Application Data

- (63) Continuation of application No. 29/830,408, filed on Mar. 11, 2022, now Pat. No. Des. 1,008,127, which is a continuation of application No. 29/802,923, filed on Aug. 9, 2021, now Pat. No. Des. 949,069, which is a continuation of application No. 29/765,018, filed on Jan. 5, 2021, now Pat. No. Des. 930,862, which is a continuation of application No. 29/735,597, filed on May 22, 2020, now Pat. No. Des. 909,934, which is a continuation of application No. 29/706,533, filed on Sep. 20, 2019, now Pat. No. Des. 888,629, which is a continuation of application No. 29/680,745, filed on (Continued)

(57) **CLAIM**

The ornamental design for a set of vehicle doors as shown and described.

DESCRIPTION

FIG. 1 is a front perspective view of the claimed design; FIG. 2 is a front view of the claimed design;

FIG. 3 is a rear view of the claimed design;

FIG. 4 is a left side view of the claimed design;

FIG. 5 is a right side view of the claimed design;

FIG. 6 is a top view of the claimed design; and,

FIG. 7 is a bottom view of the claimed design.

The ornamental design that is claimed is shown in solid lines in the figures. Evenly-spaced broken lines depict unclaimed environmental subject matter.

1 Claim, 7 Drawing Sheets

Related U.S. Application Data

Feb. 19, 2019, now Pat. No. Des. 871,283, which is a continuation of application No. 29/621,958, filed on Oct. 12, 2017, now Pat. No. Des. 843,281, which is a continuation of application No. 14/612,100, filed on Feb. 2, 2015, now Pat. No. 9,829,282, which is a continuation of application No. 13/629,009, filed on Sep. 27, 2012, now Pat. No. 8,943,946, said application No. 29/621,958 is a continuation of application No. 15/599,174, filed on May 18, 2017, now Pat. No. 10,434,995, which is a continuation of application No. 14/724,279, filed on May 28, 2015, now Pat. No. 9,656,640, which is a continuation of application No. 13/841,686, filed on Mar. 15, 2013, now Pat. No. 9,045,014.
